(57) **CLAIM**

The ornamental design for a blade-shaped motorcycle fork tree, as shown and described.

DESCRIPTION

FIG. 1 is a bottom, front left perspective view of a blade-shaped motorcycle fork tree according to the first embodiment of my invention.

FIG. 2 is an enlarged bottom, front left perspective view of the blade-shaped motorcycle fork tree of FIG. 1.

FIG. 3 is an enlarged top, front left perspective view of the blade-shaped motorcycle fork tree of FIG. 1.

FIG. 4 is a front, elevation view of the blade-shaped motorcycle fork tree of FIG. 1.

FIG. 5 is a top plan view of the blade-shaped motorcycle fork tree of FIG. 1.

FIG. 6 is a bottom plan view of the blade-shaped motorcycle fork tree of FIG. 1.

FIG. 7 is a left side, elevation view of the blade-shaped motorcycle fork tree of FIG. 1, the right side, elevation view being a mirror image thereof; and,

FIG. 8 is a rear, elevation view of the blade-shaped motorcycle fork tree of FIG. 1.

The broken lines shown in FIG. 1 are for illustrative purposes only and form no part of the claimed design.
